UNITED STATES PATENT OFFICE.

CORNELIS THEODORUS WOLDERS, OF MIDDELBURG, NETHERLANDS.

TUBE-BENDING MACHINE.

Application filed November 16, 1925, Serial No. 69,446, and in Netherlands October 11, 1923.

My invention relates to machines for bending tubes when cold.

Machines for this kind are generally provided with a core, one end of which is connected to a fixed point and the other end of which is rounded and extends to a position directly above the circumference of a rotatable clamping block, in which a groove is provided to receive the tube to be bent.

10 In order to bend a tube with a machine of this kind, the tube is slid over the core while its end is fixed to the circumference of the clamping block. Thereafter the clamping block is slowly rotated whereby the tube is bent around the clamping block, the wall of the tube being supported by the rounded end of the core.

In practice difficulty is experienced in correctly bending tubes with machines of this kind for the following reasons:

Firstly the wall of the tube is not homogeneous all over, so that the outside of the tube at some points is during bending subject to heavy stretching, while at other points it is not stretched.

Secondly the cross section of the core should be less than the inner diameter of the tube to be bent as otherwise it is impossible to slide the tubes over the core, as those tubes are usually not quite round and not smooth on the inside. Where a space is provided between the core and the tube, the tube has after bending an oval form. Moreover great friction is set up between the core and the tube, so that to effect the bending operation and to draw the tube over the core heavy forces must be exerted.

According to the present invention the above defects are obviated by rotating the core during the bending operation to facilitate which the core is preferably provided with rollers disposed at the circumference of the core. In this way the wall of the tube is so to say rolled, so that a perfectly formed bend is obtained.

According to the invention the rollers are located in openings formed in a freely rotatable container of tubular form, in which a positively driven rotatable spindle is contained, against the circumference of which the rollers bear. When the spindle of the bending machine is rotated, such movement is transmitted to the rollers by reason of the frictional contact they make with its circumference with the effect that these rollers roll

over the inner wall of the tube whereby the container can freely follow the movement of the rollers.

The spindle is preferably constructed so that it decreases in cross section towards its end and moreover can be slid relatively to the roller container in an axial direction. In this way by withdrawing the spindle it results that the rollers in the container are permitted to fall down with the effect that the tubes can be slid in and out easily.

According to the present invention the rollers are preferably placed inclined relatively to the axis of the core with the result that during the bending operation of a tube the wall of the latter so to say is rolled and friction of the rollers against the wall of the tube is prevented.

In order that the invention may be clearly understood an embodiment of the same will now be described by aid of the accompanying diagrammatic drawings in which:

Fig. 1 shows a side elevation of the machine,

Fig. 2 shows a top view of the same, and

Fig. 3 shows a detail on a larger scale of the end of the core.

Referring to the drawings, on a support 1 is rotatably mounted in bearings a shaft 2, carrying a clamping block 3. This block 3 is provided with a semi-circular groove 4 around its periphery. On the circumference of the clamping block 3 a clamping device 5 is arranged adapted to clamp the end 80 of the tube which is to be bent over said block.

At a very small distance above the clamping block 3 lies the end of a horizontally placed core 6, the other end of which is fixed 95 to the support 22 of the machine. Above and below the core are placed rollers 31 for guiding and supporting the tube to be bent.

In order to bend a tube firstly the whole tube is slid over the core 6 and afterwards 100 the end is fixed by means of the clamping device 5 at the circumference of the clamping block 3. This block is then slowly rotated whereby the tube is bent about the block and the end of the core prevents the 105 denting of the tube.

According to the invention the machine for bending tubes is constructed so that the end of the core during the bending operation of a tube is rotated. To this end the core 110

is provided with an inner rotatable shaft 8, which is connected to an electrometer 7.

On the end of the shaft 8 a spindle 9 is connected, preferably of the form as shown 5 in the drawing.

A roller container or sleeve 11 is mounted so as to be freely rotatable on this spindle preferably upon ball bearings 10. In this 10 roller container openings 12 and 13 at the circumference are made, which permit the engagement of roller 14 and 15 placed in these openings with the correspondingly shaped outer surface of the spindle 9. The 15 rollers 15 have a barrel form and the rollers 14 are cone-shaped, so as to be adapted to bear squarely against the correspondingly shaped circumference of the spindle 9. The 20 openings 12 and 13 are so arranged at the circumference of the rollers that the latter 25 can be slid inwards when the spindle 9 is displaced to the left relative to the roller container 11 (Fig. 3), whereby they are prevented from falling out of the roller container. This has the effect as mentioned in 30 the introductory part of the specification.

When the shaft 8 with the spindle 9 are rotated this movement of the spindle 9 is transferred to the rollers 14 and 15, which in the openings 12 and 13 start to rotate, 35 whereby the roller container 11 can freely follow the movement of the rollers 14 and 15.

The roller container 11 is further at one end connected to a guider 16 which together with the roller container rotates and at its 35 left end also by means of a ball bearing 17 is rotatable in the sleeve 18, forming the front part of the core 6.

The shaft 8 is rotated by the motor 7. This motor drives by means of a transmission 40 also a small oil pump 19 (Fig. 2) which supplies oil through a duct 20 to the sleeve 18 from whence the oil flows through the guider 16 and the roller container 11, from whence the oil is returned to the oil pump 45 to be used over again. All the rotating parts of the core are therefore lubricated.

Further the shaft 8 is arranged in such a way that it may be withdrawn over a certain distance in the sleeve 18. This may be effected in a simple way by arranging the 50 motor 7 on a slidable support. However other suitable means may be also applied for effecting the withdrawing of the shaft.

The openings 12 and 13 containing the 55 rollers 14 and 15 are placed inclined relatively to the axial direction, as is shown with dotted lines in Fig. 3, with the effect that in bending the tube friction between the roller and the tube is prevented. In 60 order to be able to bend tubes of different cross sections with the machine, it is only necessary to replace the roller container 11 and the spindle 9 by others of the required form.

65 In bending a tube with this bending ma-

chine the shaft 8 is first withdrawn with the spindle 9, whereby the rollers 14 and 15 slide inside. Afterwards the tube is slid in the usual way around the core and with its end, by means of a clamping device 5, 70 fixed to the block 3. The shaft 8 with the spindle 9 is then slid in again and the motor 7 is started. The shaft 2 is then driven by another power source, whereby the tube is slowly bent around the clamping block 3. 75 For removing the bent tube, the shaft 8 with the spindle 9 can be withdrawn again, in order to turn the rollers aside.

With the bending machine referred to hereabove the tubes can be bent suitably 80 in the form of a helix, for which purpose on the shaft 2 a clamping block 3 is provided having a corresponding groove and the motor 7 with the oil pump 19 is mounted upon a sliding bed 22, the driving part 85 of the machine being displaced laterally an amount corresponding with the pitch of the groove in the clamping block. In the drawing a shaft 23 is shown, which is driven by the same driving part as serves to drive 90 the shaft 2 and clamping block 3. This shaft 23 drives by means of cone wheels 24 and 25 and the wheels 26 and 27 a screw spindle 28, which extends through a corresponding screw threaded boring of the sliding bed 22. The wheel 26 is slidably mounted in axial direction for disengaging the motion.

The motor 7 is slidably mounted in axial direction on the block 40. This block 40 has 100 a screw threaded part 41 through which extend the screw spindles 29 and 30. These spindles are on the top mounted in bearings 42, which are slidable in a horizontal direction in a groove of the yoke 43. The 105 spindles 29 and 30 are also rotatable in bearings 43 fixed in the sliding bed 22. This sliding bed can slide along a support 44, which has a groove 45, in order that the spindles 29 and 30 can be laterally displaced. 110

For bending tubes in the form of a helix the rollers 31 are also mounted to move sideways together with the sliding bed 22 in accordance with the pitch of the helix to be 115 formed. For this reason the rollers 31 are grooved and mounted slidable on shafts 32.

With the machine spiral shape bends can also be formed by providing on the shaft 2 a clamping block 3 having a suitable shaped 120 groove, and whereby the block 40 is gradually lifted up by the aid of the screw spindles 29 and 30.

For this purpose on the shaft 23 a second cone wheel 32' is fixed. This wheel cooperates with a similar wheel 33, which by means of a transmission drives a horizontal shaft 35. This transmission consists of three pinions 46, 47 and 48, from which the pinion 46 is slidable in axial direction for disen- 130

gaging purposes. The shaft 35 is provided with a key groove by means of which two cone wheels 36 and 37 are slidable over the shaft 35. The wheels 36 and 37 are engaging with cone wheels 38 and 39 fixed on the lower ends of the screw spindles 29 and 30. Means are provided for maintaining the engagement of the pairs of cone wheels 36, 38 and 37, 39 during the laterally sliding movement of the sliding bed 22.

In order to form conical spirals a clamping block 3 with a suitably shaped groove is mounted on the shaft 2, while the sliding bed 22 is moved by the machine laterally and 15 the block 40 in an upwards direction, corresponding with the pitch of the winding to be formed.

What I claim as my invention and desire to secure by Letters Patent is:

20 1. In a machine for bending tubes when cold, in combination, a rotatable clamping block, means for clamping one end of the tube to be bent to the periphery of said clamping block, means for positively rotating said clamping block, a core for supporting the tube to be bent, a sleeve mounted upon one end of said core so as to be freely rotatable thereon and provided with openings, 25 rollers mounted within openings in said sleeve, a spindle extending centrally through said core and adapted to support said rollers and means for positively rotating said spindle.

25 2. In a machine for bending tubes when cold, in combination, a rotatable clamping block, means for clamping one end of the tube to be bent to the periphery of said clamping block, means for positively rotating said clamping block, a core for supporting the tube to be bent, a sleeve mounted upon one end of said core so as to be freely rotatable thereon and provided with openings, 30 rollers mounted within openings in said sleeve, a spindle the cross section of

which decreases towards its end and extending centrally through and axially slidably within said core, said spindle being adapted to support said rollers which are moved towards and away from the centre of the core in consequence of the axial movement of the 35 spindle and means for positively rotating said spindle.

3. In a machine for bending tubes when cold, in combination, a rotatable clamping block, means for clamping one end of the 40 tube to be bent to the periphery of said clamping block, means for positively rotating said clamping block, a core for supporting the tube to be bent, a sleeve mounted upon one end of said core so as to be freely rotatable thereon and provided with openings, 45 rollers mounted within openings in said sleeve, said rollers being inclined to the axial direction of the core a spindle extending centrally through said core and adapted to support said rollers and means for positively rotating said spindle.

4. In a machine for bending tubes when cold, a core, a sleeve forming an extension to one end of said core and mounted so as to be freely and independently rotatable, 50 said sleeve having two sets of openings arranged therein at an incline to the axial direction of the core, rollers located in each of said openings so as to be similarly inclined, one set of rollers being conical and the other set of rollers barrel shaped, a spindle extending centrally through said core and being axially slidably therein, said spindle having portions, the circumferences of 55 which are shaped correspondingly to the rollers in the two sets said portions being adapted to support said rollers and to move the same laterally when the spindle is moved axially.

In testimony whereof I affix my signature.

CORNELIS THEODORUS WOLDERS.
